MOP

Application filed June 25, 1928. Serial No. 288,054.

Our present invention relates to a mop of the type disclosed and claimed in our United States Letters Patent No. 1,545,510 of date July 14, 1925, and has for its object to improve the same, as will presently appear.

To the above end, generally stated, the invention consists of the novel devices and combinations of devices hereinafter described and defined in the claims.

10 In the accompanying drawings, which illustrate the invention, like characters indicate like parts throughout the several views.

Referring to the drawings:

Fig. 1 is a plan view of the complete mop, 15 some parts being broken away and other parts sectioned;

Fig. 2 is a fragmentary perspective view of the mop swab;

Fig. 3 is a view in transverse section taken 20 on the line 3—3 of Fig. 1, on an enlarged scale, with the end portions of the mop swab broken away;

Fig. 4 is a view partly in end elevation and partly in section taken on the line 4—4 of Fig. 25 1; and

Fig. 5 shows in section another form of the holder.

The mop swab is reversible and comprises 30 layers of relatively long cords 6, connected together at their longitudinal centers by a three-ply fabric strip, the plies of which are indicated by the numerals 7, 8 and 9. These plies 7, 8 and 9 extend transversely of the cord 6, thus leaving the end portions of said 35 cords loose.

The cords 6 extend between the plies 7 and 8 and which plies are preferably formed from a single piece of fabric that extends completely around said cord. The plies 7 and 8 are 40 connected together at their longitudinal edges and to the cord 6 by two rows of stitches 10 and the plies 7 and 8 are further connected together and to the cord 6 by an intermediate row of stitches 11.

45 The purpose of connecting the plies 8 and 9 together only at their longitudinal edges and not by the intermediate row of stitches 11 is to form a tube 12 from said plies through which a flexible holder for the mop 50 swab may be inserted, as will presently ap-

pear. Said holder, as shown in Figs. 1, 3 and 4 is in the form of a rubber tube 13 that is primarily straight. As shown, this flexible holder 13 has embedded therein a metal reinforcement 13^a which may be a coiled spring or 55 spring rods, but if desired this reinforcement may be dispensed with and the body of the holder so formed as to give it the necessary rigidity to keep its shape. The flexible holder 13 is adapted to be bent into the form of a loop 60 and has its end portions removably secured to one end of the handle 14 by means of a mop head 15. Said mop head 15, as shown, is made up of two duplicate pressed metal plates 16 stamped to form supplemental approximately semi-cylindrical socket-forming portions 17 and laterally spaced supplemental approximately semi-cylindrical socket-forming 65 spring clamping portions 18 for the flexible holder 13. The bodies of the plates 16 form webs between the socket-forming portions 17 and 18. Nut-equipped bolts 19 extend through aligned holes in the webs of the plates 16 and rigidly connect said plates. 70

The mop handle 14 is preferably in the 75 form of a wooden stick and the socket-forming portions 17 of the mop head fits the tapered end of said stick and are frictionally clamped thereon by the bolts 19 and rigidly held. The end portions of the flexible holder 80 13 are inserted into the socket-forming portions 18 and frictionally held thereby.

The formation of the socket-forming portions 18 is such that they are slightly sprung onto the end portions of the holder 13 at the 85 time the bolts 19 are tightened to secure the mop head to the handle 14.

In attaching the mop swab to the handle 14 the holder 13 is first inserted through the tube 12 and then the end portion of said 90 holder secured in the mop head 15, as previously described, with the plies 8 and 9 within the loop formed by the flexible holder 13 so that the cords 6 and ply 7 are on the outside of said holder, as best shown in Fig. 3. 95

As previously stated, the mop swab is reversible, thus permitting one side of the mop to be used and then turned upside down with the dirt and dust collected thereby on the top of the mop and thus held while the other 100

side of the mop is being used. When both sides of the mop swab have been used, the mop may be taken to a window or door and shaken to remove the dust and dirt therefrom. The flexible holder 13 is free for universal movements so that it will yield in all directions during the mopping action and then assume its normal position when the pressure is removed from the mop.

5 In Fig. 5 the flexible holder 20 is made from a solid piece of rubber and if desired it may be provided with a metal reinforcement.

10 What we claim is:

15 1. A mop comprising a handle, a head applied to the handle, a pliable rubber holder bent to form a loop and having its ends secured to the head, and a swab provided with means for attaching the same to said holder, said holder and swab being adapted to be sprung into various different forms but to return to normal shape when relieved from pressure.

20 2. A mop comprising a handle, a head applied to the handle, a pliable holder comprising a rubber tube bent to form a loop and having its ends secured to the head, and a swab provided with means for attaching the same to said holder, said holder and swab being adapted to be sprung into various different forms but to return to normal shape when relieved from pressure.

25 3. The structure defined in claim 1 in which the rubber holder is provided with a metal reinforcement embodied therein.

30 In testimony whereof we affix our signatures.

HERMAN J. OSTDIEK.
MARY E. HANKE.
